Patented Nov. 10, 1914.

UNITED STATES PATENT OFFICE.

JAMES ANDERSON, JR., OF OMAHA, NEBRASKA.

TELEPHONE CUT-OUT.

1,116,667.

Specification of Letters Patent.

Patented Nov. 10, 1914.

Application filed October 7, 1912. Serial No. 724,491.

To all whom it may concern:

Be it known that I, JAMES ANDERSON, Jr., citizen of the United States, residing at Omaha, in the county of Douglas and State 5 of Nebraska, have invented certain new and useful Improvements in Telephone Cut-Outs, of which the following is a specification.

This invention relates to telephones and 10 has as its object to provide in a telephone set means for breaking the transmitter circuit so that the person using the telephone may converse with a party at his end of the line without the party at the other end 15 of the line hearing what is said.

It is one aim of the present invention to provide in a telephone, a cut-out device for the purpose above mentioned which may be readily actuated by the person using the 20 telephone and while the phone is being held in the hand.

A further aim of the invention is to so construct and arrange the cut-out device that it cannot be tampered with and which, 25 when actuated to break the circuit to the transmitter, in no way affects the receiving circuit.

In the accompanying drawing, Figure 1 is a view in side elevation of a telephone 30 desk set, a portion of the standard being broken away and the cut-out device being shown in side elevation. Fig. 2 is a horizontal sectional view on the line 2—2 of Fig. 1.

35 In the drawing, the base of the telephone is indicated by the numeral 1 and supports the usual tubular standard 2 within which is arranged the usual post 3, which, as usual, supports circuit closing contacts which are 40 actuated upon release of the receiver hook.

The transmitter is indicated by the numeral 4 and the conductor which leads thereto is indicated at 5. Secured by means of screws or other securing elements 6 upon 45 one side of the post 3 is a base plate 7 upon which the circuit closing device, embodying the present invention, is mounted. A binding post 8 is located at the upper end of the plate 7 and is insulated therefrom and secured through this post is a contact leaf 9 provided at its lower end with a contact point 10, preferably of platinum. A similar binding post 11 is located at the lower end of the plate 7 and has secured to 55 it a contact leaf 12 having a contact point 13. The leaves 9 and 12 are of resilient

metal and normally the points 10 and 13 are in contact. A conductor wire 14 is connected to the leaf 12 and is lead through the base 1, as usual.

60 Apertured ears 15 and 16 project laterally from the face of the plate 7, and these ears have their apertures in axial alinement. A plunger rod 17 is slidably fitted through the aperture of the ear 16 and has a reduced 65 end 18 which is slidably fitted through the aperture in the ear 15. The formation of the reduced end 18 results in a shoulder 19 which serves a purpose to be presently explained. The wall of the tubular standard 70 2 is formed with an opening 20 and secured by means of a screw 21 to the outer end of the plunger rod 17 is the base of a push button 22 which normally fits in the opening 20, and is held in this position by means 75 of a spring 23 fitted upon the plunger rod and bearing at one end against the ear 16 and at its other end against the base of the button 22.

It will be observed from an inspection of 80 the drawing, that the extremity of the reduced end 18 of the plunger rod is normally located slightly spaced from the contact leaf 12 adjacent the free end thereof, and inasmuch as this leaf is in contact with the leaf 85 9, at such time, the circuit from the transmitter will be closed and conversation can be carried on in the usual way. However, should the user of the phone wish to converse with some one at his end of the line 90 without permitting the party at the other end of the line to hear what is said, he presses in upon the push button 22 thereby forcing the end of the reduced portion 18 of the plunger rod against the contact leaf 95 12, moving the contact point 13 out of engagement with the contact point 10 upon the leaf 9; this will result in the transmitter circuit being opened and broken as will be readily understood.

100 It will be apparent that the shoulder 19 upon the plunger rod serves to limit the inward sliding movement of said rod and consequently the contact leaf 12 cannot be sprung so far out of its normal position as to prevent its re-engagement with the leaf 9 when the button is released.

105 In the foregoing it will be understood that the principles of the invention may be embodied in a wall set as well as in a desk 110 set, and it will be further apparent that when embodied in a desk set the button 22

may be pressed to break the transmitter circuit while the phone is being held in the hand and without the necessity of resting it upon a table or other support.

5 Having thus described the invention what is claimed is:

1. In a device of the character described, the combination with a housing provided with an opening, of a base plate mounted in 10 the housing, spring contacts fixedly secured each by one end to the base plate and insulated therefrom, the free ends of said contacts normally engaging each other, spaced apart apertured ears projecting from the 15 base plate, said ears being in alinement with each other with the aperture of the ear adjacent the contacts smaller than that of the ear remote therefrom, a plunger slidably fitted in the aperture of the remote ear 20 and having a reduced portion slidably fitted in the aperture of the other ear with its end presented in spaced relation to one of the contacts, a push button secured to the outer end of the plunger and movable 25 through the opening of the housing, said push button being provided with a base interiorly of the housing to engage the housing about the opening and limit the outward movement of the plunger, the inward 30 movement of the plunger being limited by engagement of the unreduced portion of

the plunger against that ear adjacent the contacts to prevent escapement of the push button from the opening, and a spring bearing about the plunger between that each remote from the contacts and the base of the push button to normally hold the plunger with the push button extended through the opening of the housing.

2. In a device of the character described, 40 the combination with a housing provided with an opening, of resilient normally engaging contacts mounted in the housing, a plunger slidable in the housing and movable 45 to engage one contact and force it from the other, means limiting such movement of the plunger, a plate bearing over that end of the plunger remote from the contacts and engaging against the inner wall of the housing to prevent outward movement of the 50 plunger, a push button bearing against the plate and provided with a recess in its outer face, and a screw threaded through the push button and plate into the plate with its head seated in such recess, the push button extending through the opening of the housing.

In testimony whereof I affix my signature in presence of two witnesses.

JAMES ANDERSON, JR. [L.S.]
